VENEER PATCH CUTTER

Julius Peterson, Tacoma, Wash.

Application November 4, 1931. Serial No. 573,015

3 Claims. (Cl. 144—2)

My present invention relates to the art of veneer working equipment and more particularly to a veneer patch cutter.

In the production of multi-thickness veneer sheet it is necessary to cut out certain imperfections; such as small knots, holes and more particularly pitch pockets. Having cut out the defective portions of a veneer sheet, it is then necessary to insert a patch in place of the portion removed. This is normally formed like a small boat, in other words, of considerable length, narrow, and having rather sharply tapered sides. The production of this patch, however, has been quite an expensive operation in the past and it is to provide means for economically making these patches that I have provided my present machine, therefore.

The principal object of my invention is to provide a veneer patch cutter which is characterized by semi-automatic operations; so that a large number of patches can be cut in the minimum time, thus assuring the cheapest possible production of the same.

Other and more specific objects will be apparent from the following description taken in connection with the accompanying drawings, wherein

Figure 1 is a top plan view of my machine showing a strip of material from which a number of strips or patches have already been cut.

Figure 2 is a perspective view showing one of the patches.

Figure 3 is a sectional view in elevation along the lines 3—3 of Figure 1.

Figure 4 is a similar sectional view taken along the lines of 4—4 of Figure 1.

Figures 5 and 6 are views taken along the lines 5—5 of Figure 1 and illustrate two separate phases in the operation of my machine.

Referring to the drawings, throughout which like reference characters indicate like parts, number 8 designates the main table of my machine. This may be supported in any convenient manner as by legs or may be formed as a part of a bench for instance; disposed upon table 8 are two electric motors 10 and 12. These are pivotally supported upon a transverse axis from the supporting brackets 14 and 16 respectively at 15 and 17 respectively. Fixedly secured to the main shaft of the motor, are one or more saws as 18 and 19, and 20 and 21 respectively. These saws should preferably be of saucer-like shape or the so-called curved-out saws. The general disposition of the saws and their driving motors will probably be most clearly shown in Figure 1.

It is necessary in the operation of my saws to have them alternately cut and then be raised above the surface of the material they are cutting. This is accomplished by having a bracket as 22 secured to the motor. Then extending downwardly from this bracket, I provide an operating bar 23. Bar 23 is guided by the opening 25 in the table top and pivotably secured to the bracket 22 by the pivot arrangement shown at 26. At the lower end of bar 23, I have provided a roller 28 which in turn is adapted to operatively engage the cam 30. Cam 30 is fixedly secured to the driven shaft 32, which in turn may be driven by any suitable source of power as for instance, the chain drive 34.

It has been found desirable to position pivots 15 and 17 at such a distance from the saucer-like saws, that the saws will swing on a true radius. This condition, however, in view of the large size motors necessary, places the pivot axis quite a bit in front of the center of mass on the motors, and with the cam arrangement I have shown, the drop of the motors as they tilt the saws upwardly, would be too violent. To overcome this condition, I have provided a downward extending rod 24 which is fixedly secured to bracket 22. At its lowermost end I provide means for attaching a cord or cable 35 which is led upwardly over the sheave of pulley 36, and then downwardly until it is secured to the counterweight 38. The counterweight should be of such a size that it will not apply so much upward forces on the motor as to prevent it dropping downward under the influence of gravity, and withdrawing the saws from the strip.

It will be apparent I believe, that springs may be substituted for the counterweight system, however, the inertia which must be overcome in the counterweight provide a smoothness of operation which I have not been able to obtain with any spring arrangement. It is desirable to have a duplicate counterweight for each motor.

I have described the operating mechanism which tilts one of the motors. It must be understood that an exact duplicate of this arrangement is used to tilt the other motor, and normally both motor's operating equipment is timed to operate together as I have found it is the most satisfactory, there being less danger of the drift moving out of place. Now to properly understand the operation of my machine, it must be remembered that strip 40 is thin veneer wood usually somewhat thicker than the sheet of veneer it is intended to patch. This makes it possible to have the patch extend out a little bit beyond the sur-

face of a finished sheet, so that it may be dressed down to the surface of the big sheet, as the sheet goes through its final sanding operation. It should further be understood that saws 18 and 19 form the touch 41 and 43 respectively, and that a little later saws 20 and 21 form the touch 42 and 44 respectively. When the final touch 42 and 44 have been completed the chip 45 is then complete as shown in Figure 2.

- 10 Now, it is necessary to accurately position and move to successive positions the strips 40. This I accomplish by the guide members 48 and 50 and the pressing fingers 52, all of which are secured to the base 53. The pressing members 52 are provided to constantly force strips 40 over against the side guide 48. It has been found necessary to provide some means for preventing patches 45 being lodged within the multiple saws as 18 and 19 after the final touch has been made.
- 15 To overcome these conditions I provide the guide member 50 which presses down on top of strip 40 and holds the patches 45 from coming out of their positions. It will be apparent, I believe, that it is necessary to provide curved slots in bar 50, so that the saws may work through the bar and engage strip 40 to the full depth required.

Now it must be remembered that these saws operate at very high speed. Consequently it is very essential that strip 40 be held securely during the sawing operation, and then be released so that it can be moved to the next successive position required. The downwardly or holding pressure is provided by two shoes 55 and 56, which are preferably made adjustable. These shoes are fixedly secured to the downwardly extending push rods 57, which in turn are secured to the common operating bar 58. Bar 58 is provided with a cam engaging surface 59, which is preferably removable so that if through wear it becomes worn it can be easily replaced. The surface 59 is positioned to engage the pressure cam 60. Due to slight variations in thickness of strips 40 I prefer to provide the actual downward pressure by means of a plurality of springs disposed for compression as 62. As it is necessary to move strip 40 to successive positions I provide the strip engaging pawl 64 which is fixedly secured to the operating lever 66. Lever 66 is pivotably supported at 67 and has secured to its lower end the operating bar 68. Bar 68 is positioned to engage cam 70 which in turn is mounted upon and driven by the shaft 32. To properly position bar 68 I provide the guide 72 and I have further arranged to provide the retracting means by having the tension spring 74 secured to guide 72 and also to lever 66; so disposed as to at all times keep the cam engaging end of bar 68 pressed against the cam 70.

60 *Method of operation*

In operating my device both motors are started, and allowed to attain their operating speed. A strip at 40 is introduced into the guide way that is under pawl 64 up against guide 48, under 50 and arranged for the pressers 52 to engage the sides. As soon as the bar is entered under bar 50, the pawl 64 will then place the strip in proper position. The sequence of operation is exactly as follows: Cam 60 operates to raise shoes 55 and 56 upwardly, so that no pressure is provided on bar 50. The next operation is for

cam 70 and the associated mechanism to move pawl 64 toward the saws. This carries strip 40 the distance between successive patch cuts. When the operation of pawl 64 has been completed, cam 60 revolves sufficiently to allow the springs 62 to seat and secure the shoes 55 and 56, thus clamping strip 40 in position. Cams 30 then come into operation and through means of their connecting members 23 and 26 tilt the motors and their accompanying saws to the position indicated in Figure 6. Here the cut is made after which either springs or preferably gravity restore the motors with their saws listed as indicated in Figure 5. This completes one cycle of operation and after the strip has passed through, so as to be engageable by both sets of saws, two patches are produced on each rocking of the saws and as the entire mechanism is driven at considerable speed, an unbelievable number of patches can be produced in a very short time.

I have indicated my machine with one or two saws on a single shaft. It is possible, however, to use more than two saws if conditions demand increased production. The angularity, however, of the saws is such that possibly three or four saws would be the maximum which could be used by this method.

There are many features of construction which I have not illustrated completely as they will be readily apparent to one skilled in this class of work.

The foregoing description and the accompanying drawings are believed to clearly disclose a preferred embodiment of my invention but it will be understood that this disclosure is merely illustrative, and that such changes in the invention as may be made are fairly within the scope and spirit of the following claims:

Having thus fully described my invention, what I claim as new and desire to secure by Letters Patent is:—

1. In a veneer patch cutter, the combination with a pair of laterally offset, tilttable motors, and oppositely arranged bow-shaped rotary saws mounted thereon, of means for simultaneously tilting the motors at substantially the center of the spherical contour of the saws to operative position of the saws, and means for automatically retracting the tilttable motors and saws.

2. In a veneer patch cutter, the combination with a pair of laterally offset, tilttable motors, and oppositely arranged bow-shaped rotary saws mounted thereon, of a cam-shaft and cams thereon, cam arms mounted on the motors and cam devices on said arms for co-action with the cams for tilting the motors at substantially the center of the spherical contour of the saws, and means for automatically retracting the tilttable motors and saws.

3. In a veneer patch cutter, the combination with a pair of laterally offset, tilttable motors, and oppositely arranged bow-shaped rotary saws thereon, of a cam-shaft and cams thereon, cam arms pivotally connected with said motors and cam devices on said arms for co-action with the cams for tilting the motors at substantially the center of the spherical contour of the saws, and a counterweight suspended from each motor for retracting said motors and saws.

JULIUS PETERSON.
